DESIGN.

—o—
W. E. SAYERS.

CARPET.

No. 18,168.

Patented Mar. 6, 1888.

UNITED STATES PATENT OFFICE.

WILLIAM E. SAYERS, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 18,168, dated March 6, 1888.

Application filed January 26, 1888. Serial No. 262,082. Term of patent 8½ years.

To all whom it may concern:

Be it known that I, WILLIAM E. SAYERS, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures, herein specifically shown and claimed.

The accompanying photograph is a face view 15 of a carpet showing my new design.

My design consists of a number of groups or masses of varying size and outline closely arranged over the surface of the carpet. These masses are composed of various kinds of cellular-like work or small geometrical patterns or 20 honeycomb forms. The outline of each of

these groups or masses is very irregular, being formed in most cases by small projecting portions, which are rounded or partly circular in shape, giving the groups the appearance of 25 having been produced by the uniting of many small forms. The ornamentation of the central portion of the groups is very varied, but is generally geometrical in character. Between these principal masses, or adhering to their 30 edges, are small figures, such as crosses, star forms, double crosses, and other geometrical forms.

What I claim as new, and desire to secure by Letters Patent, is—

The design for carpets, consisting of the design substantially as shown.
